UNITED STATES PATENT OFFICE.

JOHN H. SATTLER, OF SAN FRANCISCO, CALIFORNIA.

COMBINED COAL AND GAS STOVE.

1,366,421.

Specification of Letters Patent. Patented Jan. 25, 1921.

Application filed May 14, 1919. Serial No. 296,980.

To all whom it may concern:

Be it known that I, JOHN H. SATTLER, a citizen of the United States, and a resident of the city and county of San Francisco and 5 State of California, have invented a certain new and useful Combined Coal and Gas Stove, of which the following is a specification.

The invention relates to stoves which may 10 be operated with gas or with coal, wood or other smoke producing fuel.

An object of the invention is to provide in 15 a stove of the class described, an oven which is efficiently and properly heated either by the gas or the coal fire.

Another object of the invention is to provide, in a stove of the class described, an oven which is quickly and evenly heated by the gas fire.

20 Another object of the invention is to provide a stove of the class described in which the hot gases from the gas fire pass through the coal fire flues, after passing through the oven.

25 A further object of the invention is to provide novel means for readily changing the stove from gas burning to coal burning condition and vice versa.

The invention possesses other advanta- 30 geous features, some of which, with the foregoing, will be set forth at length in the following description where I shall outline in full, that form of the invention which I have selected for illustration in the drawings 35 accompanying and forming part of the present specification. In said drawings I have shown one specific form of the stove of my invention, but it is to be understood that I do not limit myself to such form, since the 40 invention, as expressed in the claims, may be embodied in a plurality of forms.

Referring to the drawings:

Figure 1 is a vertical section of one form 45 1—1, Fig. 2. of stove of my invention, taken on the line

Fig. 2 is a horizontal section taken on the line 2—2, Fig. 1.

Fig. 3 is a horizontal section of the stove taken on the line 3—3, Fig. 1.

50 Fig. 4 is a vertical section of the stove taken on the line 4—4, Fig. 1.

The present invention relates particularly to the construction and arrangement of the oven, flues and gas burner within the stove, 55 so that the oven is properly heated when either the coal or the gas fire is being used,

and relates also to the arrangement of the gas fire with respect to the oven, so that the oven is quickly and evenly heated. The heat for baking or roasting is applied differently when coal is burned than when gas is burned. When coal is used as fuel, the food in the oven is heated by radiation, since the products of combustion do not come into contact with the food. When gas is employed, the food is heated by direct contact with the products of combustion, which enter the oven. In accordance with my invention, I arrange the gas burner in a combustion chamber which is in continuous communication with the oven and provide means for controlling the flow of air into the combustion chamber, so that when gas is burned, the combustion chamber may be freely open to the atmosphere, and when coal is burned, 75 communication of the combustion chamber with the atmosphere may be cut off, to prevent the entry of cold air into the oven. I also provide means for controlling the circulation of the hot gases through the oven and 80 these means are preferably connected with the air control means, so that both the air and the oven circulation are controlled simultaneously. When gas is being burned, the oven outlets are open, to permit circulation of the products of combustion through the oven, but when coal is burned, the outlets are closed to prevent circulation through the oven.

The stove of my invention is provided with 85 a suitable fire box 2, provided with a grate 3 for the burning of coal, wood or other fuel, and with an ash pit 4 below the grate. From the fire box, the gases of combustion pass into the chamber or front top flue 5, formed 95 between the top 6 of the stove and the top oven plate 7. From the flue 5 the gases pass down through the front inclined flue 8 into the front back flue 9 formed between the back 12 of the stove and the back oven plate 13. 100 From the front back flue 9 the gases pass into the front bottom flue 14 arranged between the bottom oven plate 15 and the bottom 16 of the stove. The gases then pass around the end of the partition wall 17, which extends 105 along the bottom, up the side and over the top of the oven, dividing the top, back and bottom flues into front and rear flues. The gases pass around the end of the partition wall into the rear bottom flue 18, up the rear 110 back flue 19 through the rear top flue 21 and into the flue 22 which is connected to the

chimney. A wall 23 separates the rear top flue 21 from the fire box and a damper 24 in the partition wall 17 adjacent the wall 23 is controlled by the rod 25 to permit the gases 5 to pass directly from the fire box into the chimney, when desired. When the damper 24 is closed, the gases from the fire in the fire box virtually pass around the oven twice before they enter the chimney, thereby insuring the extraction of a maximum amount of 10 heat therefrom. The oven is separated from the fire box by the front oven plate 26, and is closed at the rear by the oven plate 27 provided with a plurality of apertures through 15 which the products of combustion of the gas fire enter the oven.

Arranged behind the oven, in back of the rear oven plate, is a gas combustion chamber 28, the front wall of which is formed by the 20 rear oven plate 27. The gas combustion chamber is closed on the sides by the side walls 29, on the bottom by the bottom plate 31 which preferably lies in the plane of, or forms an extension of, the bottom oven plate 15. The chamber 28 is closed at the rear by the rear wall 32 which will be described in detail hereafter. Arranged in the gas combustion chamber 28 and preferably in the corner formed by the bottom plate 31 and the 25 rear wall 32, is a gas burner 33, preferably of substantially the same length as the chamber 28. The rear oven wall 27 is preferably provided with three elongated apertures, one aperture 34 being at the bottom of the oven, 30 the second aperture 35 being at about the center of the oven and the third aperture 36 being at the top of the oven. The apertures in the gas burner are preferably disposed so that the gas flames are directed toward the 35 rear oven wall 27, immediately above the bottom aperture 34. The rear wall 32 of the chamber 28 is curved or inclined forwardly from the bottom plane to the top plane of the middle aperture 35, to cause hot gases of 40 combustion to be directed into the oven through the middle aperture and above the curved portion 37, the wall 32 lies closer to the rear oven wall 27 forming a narrower chamber or flue 38, through which a portion 45 of the hot gases pass to the upper aperture 36. Hot gases pass into the oven through the three apertures and on account of the shape of the rear wall 32, they are distributed to 50 flow through the three apertures, thereby heating the oven quickly and evenly.

Air is admitted into the gas combustion chamber 28, through apertures 39 formed in the bottom plate 31, and the passage of air through these apertures is controlled by a 55 damper 41, which is shown in the closed position in Fig. 2. The damper 41 is arranged below the bottom plate 31 and extends longitudinally for the length of the bottom plate, and is pivoted at its center 42 to the bottom plate 31. The apertures are formed on op-

posite sides, both longitudinally and transversely, of the center of the bottom plate 31 and are of somewhat irregular shape, so that they are opened and closed by the movement of the damper about its pivot. The 70 damper is operated by a rod 43 attached to one end thereof, and extending through the back flues to the front of the stove.

The hot gases of combustion from the gas fire discharge from the oven through the 75 apertures 45 and 46 formed at the lower front ends of the front and back oven plates 26 and 13 respectively. By arranging these discharge apertures at the lower front corners of the oven the gases are compelled 80 to circulate throughout the whole oven, evenly heating it and the food therein, before they are discharged. The discharge of gases through the apertures 45 and 46 is controlled by sliding dampers 47 and 48 85 which are preferably connected to the air supply damper 41 in such manner that when the air supply is closed, the apertures 45 and 46 are closed and vice versa. When gas is being burned, all three of the dampers are 90 open, and when coal is burned, the three dampers are closed. The movement of the dampers converts the stove from a gas burner to a coal burner, and vice versa, and by connecting the dampers together, only 95 one operation is necessary to effect the conversion. The damper 47 is connected to the damper 41 by the rod 49 and the damper 48 is connected to the operating rod 43. Since the dampers 47 and 48 are moved in opposite 100 directions by a movement of the rod 43 in one direction, and since the apertures 45 and 46 are arranged close to the front of the stove, it is advisable to form one damper 48 of a plate having an aperture 51 therein, 105 which is moved into registry with the aperture 46 when the damper is open. Since the movement of the end of the damper 41 to completely open the apertures 39 is greater 110 than the necessary movement of the dampers 47 and 48, the damper 48 is connected to the rod 43 in such manner that the rod has a slight initial movement in either direction, independent of the damper. This is accomplished by passing the rod 43 through an 115 ear 52 on the damper and providing the rod with abutments 53 on opposite sides of the ear. The spacing of the abutments is such that when the rod 43 is moved through its entire operative distance, the damper 48 is 120 moved a sufficient distance to fully cover or uncover the aperture 46.

The gases discharging through the aperture 46 pass into the front back flue 9 and thence follow the path ordinarily taken by 125 the coal gases around the oven. The aperture 45 is guarded on the outside, from the ashes in the pit 4, by a shield 54 which, with the front oven plate 26, forms a flue into which the gases pass from the aperture 45. 130

A deflecting plate 55 arranged above the wall 54 prevents ashes falling from the grate into the flue. The gases discharge from the flue into the fire box and then may 5 pass directly to the chimney or around the oven through the coal gas flues.

I have provided means for readily lighting the gas burner. Arranged within the oven and forming a closed top channel with 10 the back oven plate 13, is a bar or plate of angular section 56 which is secured to the back oven plate. At its inner end, the plate 56 is provided with a hood 57 overlying one or more of the apertures in the burner, so 15 that when the gas is turned on, some of it flows outward through the channel, which terminates adjacent the oven door 58. The gas is ignited by a match at the front end of the channel, and immediately flashes back 20 and ignites the burner. Since the channel is arranged within the oven, the oven door must be opened before the gas may be ignited, thereby preventing explosions. When the gas burner is first ignited, 25 considerable moisture is formed on the inside of the door, which runs down and collects at the bottom of the door, causing the formation of rust. To prevent the collection of this water, and to cause its evaporation 30 quickly so that rust will not have an opportunity to form, I provide small air vents 59 along the bottom of the door, and the passage of air through these vents causes the rapid evaporation of the moisture. These 35 vents are preferably formed by fluting the bottom of the oven door.

I claim:

1. In a gas stove, an oven having a back 40 plate, a gas combustion chamber at the rear of said plate, a front door for the oven, and an igniting device extending from a point inside the door rearwardly through the oven to the burner in the said chamber so as to convey fuel therefrom, the fuel being ignitable only when the said device is uncovered by the opened door.

2. In a combined coal and gas stove, a front oven plate, a back oven plate, and a rear oven plate inclosing an oven, a rear 50 gas combustion chamber, said rear oven plate being provided with apertures for the admission of hot gases to the oven from said chamber, and said front and back oven plates being provided at the front of the oven, adjacent the bottom, with outlet apertures for the hot gases, whereby the oven is evenly heated by uniform distribution of heat from the combustion chamber.

3. In a combined coal and gas stove, a 60 front oven plate, a back oven plate, and an apertured rear oven plate inclosing an oven, a gas combustion chamber arranged behind said rear oven plate, a gas burner in said chamber, a damper for controlling the flow 65 of air into said chamber, outlet passages in

said front and back oven plates, dampers for controlling the flow of gases through said outlet passages, and means connecting all of said dampers together.

4. In a combined coal and gas stove, a front oven plate, a back oven plate, a top oven plate, a bottom oven plate, and a rear oven plate inclosing an oven, a flue for the gases of combustion of the coal fire arranged to convey the coal gases over the top plate, 70 down beside the back plate, under the bottom plate, and then return them along the same path, said rear oven plate being provided with apertures, and a gas combustion chamber arranged behind said rear oven 75 plate and above the oven bottom plate.

5. In a combined coal and gas stove, front and back oven plates, top and bottom oven plates, and an apertured rear oven plate inclosing an oven, a flue for the gases of combustion of the coal fire arranged to pass the gases in thermal contact with the top, back and bottom oven plates, a gas combustion chamber arranged behind said rear oven 85 plate and above the said bottom plate, and 90 a gas burner in said chamber.

6. In a combined coal and gas stove, front and back oven plates, top and bottom oven plates and an apertured rear oven plate inclosing an oven, a coal fire box arranged adjacent the front oven plate, a flue for the gases of combustion of the coal fire arranged to pass the gases in thermal contact with the top, back and bottom oven plates, a gas combustion chamber arranged behind said 95 rear oven plate, and gas outlet passages in the front and back oven plates communicating with the fire box and coal gas flue respectively for the even heating of the oven.

7. In a combined coal and gas stove, front and back oven plates, top and bottom oven plates and an apertured rear oven plate inclosing an oven, the bottom extended rearwardly beyond the rear plate, a coal 110 fire box arranged adjacent the front oven plate, a flue for the gases of combustion of the coal fire arranged to pass the gases in thermal contact with the top, back and bottom oven plates, a gas combustion chamber 115 arranged behind said rear oven plate and above the extension of the bottom plate, gas outlet passages in the front and back oven plates communicating with the fire box and the coal gas flue respectively, and 120 dampers for controlling said passages.

8. In a stove, an oven having an apertured rear oven plate, a gas combustion chamber arranged behind said plate, a gas burner in said chamber, and an igniting 125 device partly overlying said burner to collect fuel and extending forwardly through the oven to the front thereof.

9. In a combined coal and gas stove, an oven having a back oven plate and an ap- 130

ertured rear oven plate, a gas combustion chamber arranged behind said rear oven plate, a gas burner in said chamber, and a plate overlying a portion of said burner and 5 extending forwardly through the oven to the front thereof and forming with said back oven plate a gas conducting channel.

In testimony whereof, I have hereunto set my hand at San Francisco, California, this 1st day of May, 1919.

JOHN H. SATTLER.

In presence of—

H. G. PROST.
